UNITED STATES PATENT OFFICE

ROY E. HAMILTON, OF KANSAS CITY, KANSAS, ASSIGNOR, BY MESNE ASSIGNMENTS,
TO WILSON-JONES COMPANY, OF CHICAGO, ILLINOIS, A CORPORATION OF MASSA-
CHUSETTS

LOOSE LEAF BINDER

Application filed July 2, 1928. Serial No. 289,800.

This invention relates to loose leaf binders and more particularly to what is commonly known as the prong binder which comprises a pair of hingedly connected plates each having 5 arcuate filing prongs extending toward the other plate and in which sheets are so spaced apart that each sheet of a series has an uncovered portion on which any suitable identification characters may be placed to 10 produce a visible record.

One of the objects of the present invention is the provision of a loose leaf binder having hinged together back members to which covers are hinged for limited movement to 15 cause the closing of said back members as the covers are moved to the closed position.

Another object of the present invention is the contemplation of a loose leaf binder having angled back members hinged together 20 with latching means at each end thereof to limit the opening movement of the same and wherein the pintle of the hinge of the back members is employed to carry a means for releasing the latching means at both ends 25 thereof.

A further object of this invention is the provision of a loose leaf binder having two back members hingedly joined together with latching means at each end thereof, and 30 means for releasing said latching means having a pivoted lever which is normally retained in a neutral position but may be operated in two directions to release the latching means.

Further objects of this invention are simplicity of construction, ease of operation, and 35 stability when in the working position.

With these general objects in view as well as minor objects which will appear during the course of the detailed specification, the 40 invention will now be described with reference to the accompanying drawings illustrating a construction embodying the improvements of this invention.

In the drawings:
45 Figure 1 is a plan view looking into the binder in an open position, with parts broken away.

Fig. 2 is a longitudinal sectional view taken on line II—II of Fig. 1.

50 Fig. 3 is a fragmentary end elevation of

the operating end of the binder with the covers in the closed position and dotted open.

Fig. 4 is an enlarged cross section taken on line IV—IV of Fig. 1.

Fig. 5 is an enlarged cross section taken 55 on line V—V of Fig. 1, showing the back members in the closed position.

Fig. 6 is a view similar to Fig. 5, with the back members in the intermediate or working 60 position.

Fig. 7 is a fragmentary horizontal section taken on line VII—VII of Fig. 5.

Fig. 8 is a section taken on line VIII—VIII of Fig. 5.

Fig. 9 is an enlarged fragmentary section 65 taken on line IX—IX of Fig. 1, showing the cover hinge when the cover is in the open position.

Fig. 10 is a view similar to Fig. 9, with the cover shown in the closed position. 70

Referring to the drawings wherein like numerals designate like parts throughout the several views, the numerals 10 and 11 designate a pair of angular back members having hinge knuckles 12 formed in their adjacent sides to receive the pintle 13 which extends substantially the full length of the back members. Securely attached to the back members by welding or any other suitable way, are end caps 14 adapted to butt together 75 at their inner edges when the back members are in the closed position. Attached to each back member is a plate 15 having filing prongs 16 swaged or otherwise securely attached thereto and extending toward the other plate. Said prongs are arcuate and preferably concentric with the pintle 13 so that as the back members are moved the prongs will all remain in a common cylindrical surface. 80

The binder is so constructed as to provide three distinct operative positions, in which the binder may be positioned and secured against further opening, and for this purpose I have provided the following latching means and manually controlled means for releasing the same. Securely affixed by welding or otherwise to the inner face of one cap 14 at each end of the back member 85 10 is a plate 17 which overlaps the adjacent 90

end cap and facilitates the closing of the gap between the end plates when the binder is in the intermediate position as shown in Fig. 6. An inwardly extending post 18 is rigidly attached to each of the plates 17 and is preferably positioned equidistant from side walls of the back members when they are in the closed position. Securely attached to one end of the pintle 13 and extending inwardly adjacent the plate 17 at one end is an operating lever 19 provided with a finger hold 20 by means of which the lever may be moved to the right or left from a normal position, as hereinafter described. A bar 21 having an opening 23 into which is loosely fitted post 18, is secured to the end plate 17 by means of the shouldered screws 22 which allows for a slight inward movement of the bar, but which in conjunction with the post 18 prevents any oscillation of the same. The ends of the bar 21 are constructed and positioned to normally contact with the inner face of the plate 17, while the intermediate portion thereof is offset to span the lever 19 positioned between plate 17 and bar 21.

The free end of bar 21 is provided with an outwardly extending ratchet tooth 24 adapted to extend through the opening 25 in end plate 17 and into either opening 26 or 27 formed in an end cap 14 to either limit the opening of back members 11 or lock them in closed position. It will be noted that ratchet tooth 24 is so constructed with a beveled outer surface as to permit relative movement of the back members in one direction only. Openings 26 and 27 are of equal radial distances from the pintle 13 so that as the back members are oscillated about said pintle the ratchet tooth 24 will be properly positioned to engage with either of said openings.

The bar 21 is provided with an inturned lug 28 at its upper side adjacent opening 23. Operating lever 19 is also provided with an inturned lug 29 which is positioned adjacent lug 28 and coextensive therewith. A helical spring 30 having oppositely disposed hook members 31 and 32 extending outwardly therefrom is carried on the outer periphery of sleeve 33 which is secured to post 18 by means of pin 34. As clearly shown in Fig. 5, the hook members of spring 30 engage opposite adjacent sides of inturned lugs 28 and 29 respectively, thereby normally holding operating lever 19 in a central position. However it is apparent that by pressing on the finger hold 20, the lever may be moved either to the right or left against the spring action. As operating lever 19 is moved to the left the hook member 32 will retain its initial position against lug 28 while the hook member 31 will be carried to the left by means of the lug 29, thereby tensioning spring 30 and permitting the automatic return of the lever 19 to its initial position when finger hold 20 is

released. An opening 25' in lever 19 is adapted to encompass post 18 and its side walls are so positioned as to engage post 18 to limit the movement of lever 19 in both directions.

Intermediate opening 23 and ratchet tooth 24 in bar 21 is a recess 35 having inclined walls. A steel ball 36 carried in an opening 37 formed in operating lever 19 is so positioned between plate 17 and recess 35 in bar 21 that it will normally be centered therein and as lever 19 is operated ball 36 will impinge the inclined wall of recess 35, thereby forcing ratchet tooth 24 inwardly to disengage from either opening 26 or 27 as the case may be, thus permitting further opening of back members. A coil spring 55 is positioned around post 18 between sleeve 33 and bar 21 tensioned to normally force ratchet tooth 24 into the openings.

Both ends of the binder may be similar in construction; however, I have chosen to eliminate the manual operating lever at one end and therefore have slightly modified some of the parts.

Bar 21' has a central opening 23' into which the post 18 is fitted and is secured at one end for limited inward movement by a shouldered screw 22. The free end of bar 21' is provided with an outwardly extending ratchet tooth 24' which is normally held against inward movement by a tensioned spring 55 positioned on post 18 intermediate bar 21' and sleeve 33 which is securely attached to post 18. A lever 38 secured to pintle 13 by means of pin 39 is operable thereby. Lever 38 has an opening 37' which is adapted to receive a ball 36 which in turn is positioned between the inner surface of plate 17 and a recess 35' having inclined walls formed in bar 21' and impinges said inclined walls to cause the inward and outward movement of said bar as the lever 38 is moved in either direction.

Back members 10 and 11 are each provided with hinge knuckles 46 which cooperate with hinge knuckles 47 formed at the ends of covers 48 to receive pintles 49 for hinging said back members and covers together. Knuckles 46 and 47 are provided with interlocking projections 50 and 51 respectively, which coact to limit the hinging movement between the covers and back members for purposes hereinafter set forth. Fig. 3, shows the binder in solid lines in the closed position. The covers 48 are free to move outwardly to the position shown in dotted lines without interfering with the relative positions of the back members 10 and 11. However, as clearly shown in Fig. 10, when cover 48 and the outer wall of back member 10 are in alignment, 48 cannot be moved farther inwardly if the back members are in the closed position. Whenever the binder is in the completely open position or the partially open or working position as shown in Fig. 6, the binder

may be closed to the position shown in Fig. 3, by simply grasping the covers and moving them inwardly. With the ratchet tooth as shown the back members when in the full open position may be moved to the closed position and said tooth will ratchet past opening 27 and drop into opening 26 to secure the backs against accidental opening.

From the foregoing it is apparent that the present invention provides a loose leaf binder mechanism in which the back members can have no movement relative to the covers when the covers are in the closed position, and also provides a mechanism which will permit the positioning of the binding prongs in the closed, working, or open position as desired.

I do not wish to limit this invention to the structure shown and described, as many modifications may be made within the scope of the appended claims without departing from the spirit thereof.

What I claim is:

1. In a loose leaf binder, a pair of back members, a pintle pivotally connecting said back members, a latching mechanism having interengaging parts carried by the back members to secure the back members against opening, and means carried by the pintle operable in two directions from a neutral position to disengage the interengaging parts of the latching mechanism.

2. In a loose leaf binder, a pair of back members, a pintle pivotally connecting said back members, a latching means having interengaging parts carried by the back members at each end thereof to secure the back members against opening, means carried by the pintle operable in two directions to disengage the interengaging parts of the latching means, and mechanism normally securing said disengaging means in the inoperative position.

3. In a loose leaf binder, a pair of back members, a pintle pivotally connecting said back members, a latching means having interengaging parts carried by the back members at each end thereof to secure the back members against opening, and disengaging means automatically returnable to its inoperative position carried by the pintle and movable to disengage the interengaging parts of the latching means.

4. In a loose leaf binder, a pair of back members, a pintle pivotally connecting the back members, an outer end member carried by one of said back members and provided with openings, an inner end member carried by the other of said back members, formed to overlap said outer end member, a latching bar having a tooth adapted to selectively enter said openings, said bar being carried by the inner end member, and means to actuate said bar through the intermediacy of said pintle whereby the tooth is removed from any opening with which it may be engaged.

5. In a loose leaf binder, a pair of back members, a pintle pivotally connecting said back members, a latching mechanism comprising a latch carried by one back member, detents on said other member for engaging said latch to lock said members in closed or partly open positions, and means operable by said pintle for disengaging said latch from said detents for permitting said members to move to a full open position.

6. In a loose leaf binder, a pair of back members, a pintle pivotally connecting the back members, closure members at each end of said back members, latch means mounted on the inner faces of said closure members and movable by said pintle to permit opening of said back members, and means manually operable from a point without said closure members for moving said pintle to unlock said latch.

7. In a loose leaf binder, a pair of back members, a pintle pivotally connecting the back members, closure members at each end of said back members, a latch mounted on the inner face of one of said closure members and having means for engaging a detent on the other closure member, means for moving said latch inwardly of the closure members to disengage the same, said last named means being movable by said pintle.

8. In a loose leaf binder, a pair of opposed back members having latch carrying portions at the ends thereof, a pintle pivotally connecting said back members, bars having means cooperating with the latch carrying portions of the back members to hold the latter against opening and yieldable lengthwise of the back members, and releasing means at the opposite ends of the back members and connected for simultaneous operation through said pintle each releasing means including a member swingable transversely of the back members and having means cooperating with the respective bar for moving the latter to released position.

9. In a loose leaf binder, a pair of opposed back members, a pintle pivotally connecting said back members, a latching means having interengaging parts carried by said back members to secure the latter against opening, said latching means also including a bar, and releasing means consisting of a lever secured to the pintle, and a ball movable with the lever against the bar to shift the interengaging latch parts to released position.

10. In a loose leaf binder, a pair of opposed back members, end caps therefor, a pintle pivotally connecting the back members, a latching means having interengaging parts carried at each end respectively of the back members by said end caps and including a bar to secure said back members against opening, and releasing means including a lever secured to each end of the pintle, and a floating ball carried by the lever and movable

therewith against the respective bar to release the latch means.

11. In a loose leaf binder, a pair of back members, a pintle pivotally connecting the back members, a latching means having interengaging parts carried by the back members at each end thereof to secure said back members against opening, said mechanism including bars shiftable lengthwise of the

10 back members and having cam portions, and releasing means including a lever secured to each end of the pintle, and a movable element carried by each lever and shiftable therewith against the cam portion of the respective bar to release the latter.

12. In a loose leaf binder, a pair of opposed pivoted back members, latching means to secure the back members against opening and including spring controlled latch bars located at the opposite ends of the back members and yieldable lengthwise of the latter to release therefrom, and releasing means at the opposite ends of the back member, connected for simultaneous operation, each releasing means including a member swingable transversely of the back members and having means cooperating with the respective latch bar to force the latter to released position.

30 In testimony whereof, I hereunto affix my signature.

ROY E. HAMILTON.
